DRYING, DISTILLING AND CALCINING
MACHINE
George E. Carlson, Oakville, Iowa 52646
Filed Sept. 8, 1964, Ser. No. 394,745
3 Claims. (Cl. 266—16)

This invention pertains to drying, distilling and calcining machines and more particularly to a machine designed to distil mercury or other volatile metals from mining ore.

Heretofore the machines used for distilling volatile metals from mining ore have been of the blast furnace type with a resultant variation of temperature and loss of control of the critical temperature for distilling. Furthermore machines for this purpose required a coolant to be used in connection therewith. Particularly useful for the mining of volatile ore is a machine that is small and compact for portability.

It is therefore an object of this invention to provide a machine for drying, distilling and calcining that provides constant temperature in the furnace.

Another object of this invention is to provide a drying, distilling and calcining machine that is small and compact so that it is highly portable.

Another object of this invention is to provide a drying, distilling and calcining machine that employs a continuous feed the speed of which can be controlled independently of the means for propelling ore through the machine.

Further objects and advantages of this machine will become more apparent from the following drawings, descriptions and claims.

FIG. 1 is an elevation view of the machine having a partial sectional view of the inside of the furnace and the condenser pipes. FIG. 2 is a top view of a bottom half of the furnace and a sectional view of the screw feed taken on line A—A.

In the drawings a furnace 1 has an inner casing 2 and an outer casing 3. The space between them is filled with an insulating material 4 such as asbestos. A table 5 is located inside the furnace 1 so as to be rotatable. A spiral 6 having cross arms 7 welded thereto is positioned on the table 5. The table 5 has a lip 8 at its outer edge. The spiral 6 has sliding contact with the table 5 and its lip 8. There are slots 9 in the inner casing 2. The cross arms 7 extend into the slots 9. The spiral 6 can thus move up and down in relation to the table 5 and is also held stationary as the table 5 turns. A screw 10 feeds ore from a hopper 11 onto the table 5. The screw 10 is rotatable in a tube 12. A cap 13 screws onto the tube 12 holding a seal 14 against the tube 12. The seal 14 also seals the space between a drive shaft 15 for the screw 10 and the cap 13. The tube 12 has a support 16 fastened to the outer casing 2 by the nuts 17. Heating elements 18 are positioned in the furnace 1.

The table 5 has a discharge pipe 19 at its center. The discharge pipe 19 fits through a sleeve 20. The sleeve 20 joins the inner casing 2 and the outer casing 3. A cup nut 21 screws onto the sleeve 20. A seal 22 fits into the cup nut 21 sealing the space between the cup nut 21 and the sleeve 20 and the space between the discharge pipe 19 and the sleeve 20. The discharge pipe 19 is held from sideward motion by the bearing 22A. A worm gear 23 has as an integral part of it the clamp 24. The clamp 24 is tightened on the discharge pipe 19 by means of the nut and bolt 25. A drive shaft 26 carries a screw gear (not shown) which engages the worm gear 23. The drive shaft 26 is carried in bearings 27. The worm gear 23 rides on carrier bearing 28. Legs 29 are fastened to the outer casing 3. Arms 30 fastened to the legs 29 support the bearing 22A. The bearings 27 and the car-

2

rier bearing 28 are fastened to the base 31. Two of the several legs 29 are shown in part and may extend any length below the discharge pipe 19.

A vapor pipe 32 is attached to the inner casing 2 and extends upward through the outer casing 3 and into condenser pipe 33. The condenser pipe 33 is attached to the uppermost part of the outer casing 3. Condenser pipe 34 is attached to the condenser pipe 33 by means of nuts and bolts 35. Stack 36 is attached to the condenser pipe 34 by means of nuts and bolts 37. Baffles 38 are secured to the sides of the condenser pipes 33 and 34. Collecting tubes 39 slide onto the outer ends of the condenser pipes 33 and 34.

The top and bottom parts of the furnace 1 are held together by a series of nuts 40 and bolts 41 and brackets 42 and 43 of which one of each are shown in FIG. 1. Bolts 41 are pivotable in brackets 42 which are attached to the lower part of outer casing 3. Bolts 41 pivot into brackets 43 which are attached to the upper part of outer casing 3. Seal 44 is held between the upper and lower parts of the furnace 1 when the bolts 41 are in place in brackets 43 and nuts 40 are tightened thereon as shown in FIG. 1.

The temperature in the furnace 1 may be controlled by means of gage switches (not shown) connected to the heating elements 18. Motors (not shown) are used to turn the drive shafts 15 and 26. Gage switches may also be connected to the motors.

Ore is placed into the hopper 11. As the screw 10 is turned, the ore is forced through the tube 12 and onto the table 5. The turning of the table 5 by the worm gear 23 with the spiral 6 in place causes the ore to move toward the center of the table 5. During the time the ore is on the table 5 it is heated and the fumes escape through the vapor pipe 32 and into the condenser pipes 33 and 34. As the vapor is directed toward the collecting tubes 39 by the baffles 38 it is cooled and condenses allowing the distillate to be collected by placing a container under the collecting tubes 39. When the heated ore reaches the center of the table 5 it falls into the discharge pipe 19 and may be collected in a container placed under the discharge pipe 19. The speeds at which the screw 10 and the table 5 turn may be varied in relation to each other or in relation to the temperature of the furnace 1 depending on the particular ore used. As the table 5 turns the ore is turned over many times due to its movement around the spiral 6 thus giving thorough heating of the ore. The weight of the spiral 6 causes the table 5 to be scraped clean as the ore moves on the table 5. If necessary to condensing the vapor more condenser pipes may be added above condenser pipe 34 and stack 36 put at the top of the additional condenser pipes. The collecting tubes 39 are removable from the condensing pipes 33 and 34 so that the condensing pipes 33 and 34 may be scraped clean from time to time.

It is to be understood that various types of heating elements 18 may be used in this machine, such as electricity or gas. Also it is to be understood that this machine may be used for drying material other than ore, such as grain. The size of the ore that is to be heated can vary within certain limits in a specific machine, however it is obvious that the machine could be built larger or smaller to accommodate various size material. In the event that the vapor is of such weight that it will not rise through the vapor pipe 32 and into the condenser pipes 33 and 34, a vacuum fan may be inserted in the upper portions of the vapor pipe 32 to draw the vapor upwards from the table 5. Since this machine is a continuous feed machine, it can be run continually with the discharge 70 being carried away from the furnace 1 and the vapor carried upwards and into the collecting tubes 39.

It is to be noted that the furnace 1 has only one mov-

ing part located therein, that being the table 5. Thus the size of the furnace 1 can be made smaller than other type furnaces used for these purposes. This results in a greater conservation of heat than in other furnaces used for these purposes.

I claim:

1. A drying, distilling and calcining machine comprised of a furnace, heating elements located in the furnace, a screw feed protruding into the furnace, a hopper attached to the screw feed, a rotatable table in the furnace having a lip at its outer edge, a spiral in sliding contact with the surface of the table and the lip of the table, a discharge pipe at the center of the table, a vapor pipe connecting the furnace with condenser pipes, collecting tubes that slide onto the ends of the condenser pipes, means to turn the table and the screw feed.

2. A drying, distilling and calcining machine comprised of a furnace, heating elements located in the furnace, a screw feed protruding into the furnace, a hopper attached to the screw feed, a rotatable table in the furnace having a lip at its outer edge, a spiral in sliding contact with the surface of the table and the lip of the table, cross arms attached to the spiral and extending into vertical slots in the furnace, a discharge pipe at the center of the table, a vapor pipe connecting the furnace with several condenser pipes, baffles connected to the sides of the condenser pipes, collecting tubes that slide onto the ends of the condenser pipes, means to turn the table and the screw feed.

3. A drying, distilling and calcining machine comprised of a furnace having an inner casing and an outer

5 10 15
